FEED PAWL FOR A ROTARY
BATTERY IN A LOOM

John H. Blackburn, Uxbridge, Mass., assignor, by mesne assignments, to John Donald Marshall and Horace L. Bomar, Spartanburg, S.C., as trustees, in a trust known as "The Carolina Patent Development Trust"

Filed Jan. 3, 1967, Ser. No. 5,259

Term of patent 14 years

(Cl. D92—15)

FIGURE 1 is a side perspective view of a feed pawl for a rotary battery in a loom embodying my new design;

FIGURE 2 is a side elevational view of the side opposite that shown in FIG. 1; and

FIGURE 3 is a cross section thereof, taken on line 3—3 in FIGURE 2.

I claim:

The ornamental design for a feed pawl for a rotary battery in a loom, substantially as shown.
